DESK SET

Heinz Fauth, 263 Mangenberger Str.,
565 Solingen-Merscheid, Germany

Filed Feb. 25, 1969, Ser. No. 15,909
Claims priority, application Germany Jan. 7, 1969

Term of patent 14 years

Int. Cl. D19—02

U.S. Cl. D74—5

FIG. 5

FIG. 6

FIG. 7

FIG. 8

FIG. 1 is a perspective view of a desk set showing my new design,

FIG. 2 is a side view of the base portion thereof as it appears without the pen,

FIG. 3 is a plan view thereof, and

FIG. 4 is a view from below,

FIG. 5 is a perspective view of another embodiment of the desk set of FIG. 1 wherein the concavity and grooves on the sides of the base portion have been omitted,

FIG. 6 is a side view of the base portion as it appears without the pen,

FIG. 7 is a plan view thereof, and

FIG. 8 is a view from below.

I claim:

The ornamental design for a desk set, as shown and described.
